UNITED STATES PATENT OFFICE.

GEORGE LOWELL MATHER, OF AKRON, OHIO.

CORE.

1,097,937.

Specification of Letters Patent. Patented May 19, 1914.

Application filed October 18, 1912. Serial No. 726,520.

To all whom it may concern:

Be it known that I, GEORGE LOWELL MATHER, a citizen of the United States, residing at Akron, in the county of Summit and State of Ohio, have invented new and useful Improvements in Cores, of which the following is a specification.

This invention relates to improvements in collapsible cores for manufacturing the outer-shoes of double-tube pneumatic tires, and the object thereof is to provide a collapsible core which may be quickly assembled or collapsed, the invention contemplating the provision of a plurality of segments, which, when united, will form an annular core-body for imparting to the interior of the tire-shoe, during the manufacture thereof, the proper shape to receive the inner inflatable tube, the invention more particularly residing in the means whereby the various segments constituting the body portion of the core, are temporarily held in their expanded or open position.

The primary object of the invention is to construct the device that one of the segment-shaped members constitutes a wedge-shaped key, the inward removal of which permits the ends of the two adjacent segments which normally abut against the key to be swung inwardly toward each other, the opposite ends of which are hinged to opposite ends of a fourth segment to thereby permit the core to be collapsible to permit its removal from the interior of a tire-shoe after the removal of the initial key member.

The invention further and more particularly contemplates providing the inner faces of the initial key member and the two adjacent hinged segments with inclined inner faces, and the two hinged segments are provided with shoulders constituting abutments for the ends of an approximately semi-circularly-formed locking element which is in the form of a trapezium in cross section, with the inclined face of the locking member opposing the inclined faces of the key member and the two hinged members, so that when forced laterally into position the locking member holds the assembled members of the core in open position and is itself held in position by means to be more specifically described later.

With the foregoing and other objects in view, the invention consists in the novel construction, combination and arrangement of parts constituting the invention to be here-

inafter specifically described and illustrated in the accompanying drawings which form a part hereof wherein is shown the preferred embodiment of the invention, but it is to be understood that changes, variations and modifications can be resorted to which come within the scope of the claims hereunto appended.

In the drawings in which similar reference numerals indicate like parts in the different figures, Figure 1, is a plan view of a ring core embodying this invention; Fig. 2, is a view similar to Fig. 1 with the initial key removed and with the hinged members moved inwardly toward each other so that the core is in its collapsed condition ready for removal from a tire shoe; and, Figs. 3, 4 and 5, are transverse sectional views on lines X, Y, Z, of Fig. 1, respectively.

The ring core is constructed of a plurality of segment-shaped members, which when assembled together in their expanded or open position as hereinafter more fully described, constitute an annulus the outer face of which is adapted to impart the desired configuration to the inner surface of a tire-shoe to be manufactured thereon. These segment-shaped members are designated in the drawings by the reference numerals 1, 2, 3 and 4. The segment-shaped members are preferably cored or made hollow to reduce the weight of the entire core and the ends of each segment are preferably closed to present a smooth surface, so that when the segments are assembled with their ends in abutting relation they form a complete annulus. Each of the segment-shaped members is further provided with an inwardly-extending flange 5.

The joints of the segment-shaped members 2, 3 and 4 are radial to the axis of the core while the lines of severance or joints 6 between the key member 1 and the abutting members 2 and 3 are at an angle with respect to the radii of the core and so inclined as to make the member 1 practically wedge-shape. At the ends of the flange 5 of the member 4 are inwardly extending ears 7 and the ends of the members 2 and 3 which abut against the member 4 are also provided with ears 8 complementary to the ears 7, both of the members of each pair of ears being apertured to receive pivot bolts 9 for hinging the segments 2 and 3 to the segment 4. The opposite ends of the members 2 and 3 are fashioned to abut against the end walls

of the key member 1. The flanges 5 of the members 2 and 3 are cut away at 10 to form shoulders which constitute abutments for a purpose to be later described. The inner 5 faces of the members 1, 2 and 3 are transversely inclined as shown at 11 in Fig. 5. The members 1, 2 and 3 are also provided with approximately radial apertures, preferably frusto-conically-formed for a purpose to be later described.

10 In order to hold the parts in assembled relation in their expanded position a locking member 12 is employed which embodies an approximately semi-circularly-formed 15 member preferably in the form of a trapezium in cross-section with its outer face inclined and adapted to engage the inclined faces of the member 1, 2 and 3. The member 12 is also provided with a plurality of apertures adapted to register with the frusto-conically-formed radial apertures in the members 1, 2 and 3.

15 In setting up a core constructed in accordance with this invention, the parts are assembled with the key or wedge-shaped member 1 positioned between the free ends of the members 2 and 3 and the locking member 12 is forced laterally against their inner inclined faces and with its ends positioned 20 against the shoulders 10. When the member 12 is forced into position a plurality of tapered pins 13 are inserted in the apertures in the members 1, 2, 3 and 12 which hold the locking member from lateral shifting. 25 When thus set up the core is ready for use and after a tire has been vulcanized thereon the pins 13 are removed by drawing them 30 inwardly toward the axial line of the core after which the locking member 12 is shifted 35 laterally sufficiently to permit its complete removal. After this operation the key member 1 is drawn inwardly toward the center of the core and bodily removed, then the free ends of the members 2 and 3 are swung 40 toward each other into the position shown in Fig. 2 after which the collapsible core is 45 readily removed from the interior of a tire-shoe.

I claim:

50 1. In a collapsible core for the manufacture of tire-shoes, the combination of a series of segmental-shaped sections adapted to be assembled into a circular core, the ends of the sections abutting against each other 55 and formed with inwardly-extending flanges, two of said sections hinged to opposite ends of a third section, the free ends of said hinged sections having faces adapted to form a wedge-shaped space between them, a 60 wedge-shaped key member adapted to be temporarily inserted between said ends, the inner faces of said key member and said hinged members being transversely inclined, and an approximately semi-circularly- 65 formed transversely shiftable locking mem-

ber having an outer inclined face adapted to be inserted within said core with its inclined face engaging the inclined faces of said key member and said hinged members and arranged when shifted laterally against the inner faces of said members to temporarily hold them in their open or expanded position.

2. In a collapsible core for the manufacture of tire-shoes, the combination of a series of segmental-shaped sections adapted to be assembled into a circular core, the ends of the sections abutting against each other and formed with inwardly-extending flanges, two of said sections hinged to opposite ends of a third section, the free ends of said hinged sections having faces adapted to form a wedge-shaped space between them, said sections further provided with recesses, a wedge-shaped key-member adapted to be temporarily inserted between the ends of said hinged sections, said key member provided with a recess, the inner faces of said key member and said hinged member being inclined, and an approximately semi-circularly-formed locking member having an outer inclined face adapted to be inserted within said core with its inclined face engaging the inclined faces of said key member and said hinged member for temporarily holding them in their open or expanded position, said locking member provided with apertures registering with said recess, and pins arranged to be passed through said apertures and into said recess for temporarily locking said locking-member in position.

3. In a collapsible core for the manufacture of tire shoes, the combination of a series of segmental-shaped sections adapted to be assembled into a circular core, the ends of the sections abutting against each other and formed with inwardly-extending flanges, two of said sections hinged to the opposite ends of a third section, the free ends of said hinged sections separated from each other and provided with faces adapted to form a wedge-shaped space between them, a wedge-shaped key capable of being inserted in the said space completing the core, and a curved locking member arranged to be inserted within the core by being laterally shifted to position, the interengagement between the outer face of the locking member and the inner faces of the core members when said locking member is shifted transversely serving to hold said core members in their open or expanded position.

4. In a collapsible core for the manufacture of tire shoes, the combination of a series of segmental-shaped sections adapted to be assembled into a circular core, the ends of the sections abutting against each other and formed with inwardly-extending flanges, two of said sections hinged to the opposite

ends of a third section, the free ends of said hinged sections separated from each other and provided with faces adapted to form a wedge-shaped space between them, a wedge-shaped key capable of being inserted in the said space completing the core, a curved locking member arranged to be inserted within the core by being laterally shifted to position, the interengagement between the 10 outer faces of the locking member and the inner faces of the other members when said

locking member is shifted transversely, serving to hold said core members in their open expanded position, and means for holding said locking member in position.

15

In testimony whereof I have hereunto set my hand in presence of two subscribing witnesses.
